To all whom it may concern:

Be it known that I, Charlotte Marie Neuhardt, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design, and

The characteristic feature of my design resides in the combination on the two piece dress disclosed having a superimposed front yoke and a series of superimposed top pleats extending from the yoke to the bottom of the blouse, in association with a stitched collar and turned up cuffs, all as shown.

I claim:

The ornamental design for a dress, substantially as shown and described.
